US00D799972S

(12) **United States Design Patent** (10) **Patent No.:** **US D799,972 S**
Jost et al. (45) **Date of Patent:** **** Oct. 17, 2017**

(54) **BOTTLE**

(71) Applicant: **Berlin Packaging, LLC**, Chicago, IL (US)

(72) Inventors: **Scott Jost**, Chicago, IL (US); **James Tobin**, Chicago, IL (US)

(73) Assignee: **Berlin Packaging, LLC**, Chicago, IL (US)

(**) Term: **15 Years**

(21) Appl. No.: **29/572,196**

(22) Filed: **Jul. 26, 2016**

(51) LOC (10) Cl. **09-01**

(52) U.S. Cl.

USPC **D9/528**; D9/563; D9/568; D9/570; D9/575

(58) **Field of Classification Search**

USPC ..... D9/651, 658, 523-524, 528, 530-535, D9/548, 549-550, 574, 575, 520, 522, D9/526, 527, 553, 555, 556, 557, D9/563-570, 742; 215/381-385; 220/660, 669, 679, 752; D23/211.1 CPC B65D 23/00; B65D 23/10; B65D 1/00; B65D 1/02; B65D 21/00; B65D 21/02; B65D 21/0201; B65D 21/0209; B65D 21/0233; B65D 21/0234; B65D 21/0237; B65D 1/10; B65D 1/40; B65D 1/42; B65D 11/04; B65D 2501/0081; B65D 2101/0053; B65D 1/0223

(57) **CLAIM**

The ornamental design for a bottle, as shown and described.

DESCRIPTION

FIG. 1 is a right side perspective view showing the new design for a bottle;

FIG. 2 is a front left side perspective view thereof;

FIG. 3 is a left side perspective view thereof;

FIG. 4 is a rear perspective view, taken from beneath the bottle;

FIG. 5 is a rear left side perspective view, taken from beneath the bottle;

FIG. 6 is a left side perspective view, taken from beneath the bottle;

FIG. 7 is a right side view thereof;

FIG. 8 is a left side view thereof;

FIG. 9 is a rear view thereof;

FIG. 10 is a front view thereof;

FIG. 11 is a top plan view thereof; and,

FIG. 12 is a bottom plan view thereof.

The broken lines immediately adjacent to claimed subject matter represent the bounds of the claim, while other broken lines represent environmental subject matter; the broken lines form no part of the claimed design.

1 Claim, 12 Drawing Sheets
